J. A. GASKILL.

COMBINATION DOUBLE MUFFLE PREHEATING AND HEAT TREATING FURNACE.
APPLICATION FILED MAY 23, 1919.

1,403,313.

Patented Jan. 10, 1922.

UNITED STATES PATENT OFFICE.

JAMES A. GASKILL, OF CLEVELAND, OHIO.

COMBINATION DOUBLE-MUFFLE PREHEATING AND HEAT-TREATING FURNACE.

1,403,313.

Specification of Letters Patent. Patented Jan. 10, 1922.

Application filed May 23, 1919. Serial No. 299,365.

To all whom it may concern:

Be it known that I, JAMES A. GASKILL, a citizen of the United States, and resident of Cleveland, in the county of Cuyahoga and State of Ohio, have invented certain new and useful Improvements in Combination Double-Muffle Preheating and Heat-Treating Furnaces, of which I hereby declare the following to be a full, clear, and exact description, such as will enable others skilled in the art to which it appertains to make and use the same.

The objects of the invention are to provide a closed furnace for heat treating steel and other alloys, in which the metal is treated by radiation and conduction while confined in a muffle, instead of by contact with the products of combustion, as in an open hearth furnace.

20 By this means the metal is prevented from absorbing injurious gases and impurities from the heating agencies, and is also heated more uniformly and is protected from blasts of cold air, which decarbonize and crack or blister the steel; other advantages are found in the manner of construction which protects the operator from blasts of flame.

It includes a main combustion chamber which is employed as a heating chamber 30 and means for obtaining a super-heated air blast which enables the operator to raise the temperature at the combustion point more quickly, and also in conjunction with the use of oil or gas to obtain a better control of 35 the heat and at less cost for fuel. The hot air will also vaporize the oil and prevent the burner from clogging, and also prolong the life of the crucible, or muffle.

The invention includes a pre-heating 40 chamber, supplied with heat from the combustion chamber and in which metal parts to be treated are enclosed in a muffle. In this chamber the temperature is increased gradually in the metal to be subjected to the 45 higher temperatures of the combustion chamber, before introducing them therein.

This pre-heating chamber is also employed as a drawing chamber, for reducing the temperature of hardened products which have 50 been previously treated in the combustion or main heating chamber. By means of the pre-heating chamber the temperature is reduced or drawn gradually to bring the metal to the color required.

55 The objects of employing first the pre-heating and afterwards the heat-treating

chamber are also to prevent warping and irregular heating of the metal products.

The combustion chamber is also so constructed that it can be converted into a 60 melting furnace by removing the upper pre-heating chamber and substituting a crucible for a muffle therein.

The furnace is also designed to take the place of the more expensive electric furnaces 65 and for melting all ordinary material such as steel, semi-steel, grey iron, all high alloyed steels or low carbon steel, and all other metal alloys or glass, and will produce a temperature of 3,000 degrees and upward 70 according to the number of burners employed.

The air blast is automatically heated before commingling with the fuel by contact with the heated walls of the combustion 75 chamber, which it traverses in a spiral direction in an unobstructed annular chamber, in which the pressure and temperature of the blast are equalized at all the outlet nozzles.

The addition of the super-heated air to the oil fuel quickly raises the temperature of the furnace which increases in degree as long as the furnace is in use.

The invention comprises, the combination 85 and arrangement of parts and construction of the various details hereinafter described, shown in the accompanying drawings and specifically pointed out in the claims.

In the drawings Fig. 1 is a vertical section of the combined heat treating and pre-heating and drawing chambers. Fig. 2 is a plan thereof. Fig. 3 is a plan of the bottom doors of the furnace. Fig. 4 is a longitudinal section of a combination gas and oil fuel 90 burner adapted for use in this furnace.

In these views A is the outer wall of the combustion chamber, B is an annular air chamber encircling the same, C is the inner wall and D is a fire brick lining having a 100 projecting portion D intermediate of the top and bottom. Underneath the projection or shoulder D' formed thereby, the burner nozzles E, E, discharge into the combustion chamber F and underneath the muffle G, 105 which contains the metal products to be heat-treated.

The projection provides a heat retarding chamber H underneath the muffle and a heat expanding and retarding chamber I at the 110 top of the chamber. This construction prevents the direct escape of the hot products of

combustion and retains them in close proximity to the muffle.

The air blast is introduced tangentially at B' near the base of the combustion chamber 5 and the air passes spirally upward through the open unobstructed annular air chamber in close contact with the walls of the chamber and issues through pipes J, J, of reduced size at the upper end. The air is then carried 10 downward into the mixing chambers K, K, through which the fuel supply nozzles L, L, pass and into discharge nozzles E, E. Valves M, M, control the fuel supply and valves N, N, control the air supply to the 15 nozzles. The annular chamber B permits the air to expand and become highly rarefied by the extreme heat of the combustion chamber, and since it contains a large volume of air at a time the pressure and temperature there- 20 at will become equalized before it issues from the pipes J, J.

In Fig. 4 a form of burner is shown adapted for use alternately with fuel and gas. Here O is an oil supply pipe having 25 a fine terminal orifice O' through which the oil is projected. Concentrically arranged in relation thereto is a gas supply pipe P having perforations P' at its outer end through which the gas is discharged. O² and P² are 30 the respective oil and gas pipes leading to a common union P³.

In the combustion or heat treating chamber, a muffle G is supported upon brick G', and the furnace is provided with a door G² 35 which gives access thereto. The muffle closes the opening G³ in the chamber wall through which it is introduced and prevents the blast from injuring the face of the operator. A pyrometer tube R is inserted in the muffle 40 through the rear of the chamber. A central opening S is formed in the bottom of the chamber to take care of occasional overflow from the muffle. This opening is continued through the edges of the folding doors, T, T, 45 which can be dropped if necessary to discharge the contents of the chamber or repair the lining. A heavy tile V covers the top of the combustion chamber and the draft issues through the central opening V' into 50 the pre-heating and drawing chamber W. This chamber contains the muffle W' into which the metal products to be heat treated are first introduced to remove the chill and to

and the temperature can be gradually raised until they can be introduced into the main chamber with safety.

The combustion chamber can be employed as a melting furnace by removing the upper 70 chamber and substituting a crucible for the muffle in the combustion chamber.

The use of the hot air blast in this furnace serves to produce a higher degree of temperature than could be otherwise obtained with 75 oil fuel, because the dry hot air assists in vaporizing the fuel and prevents the deposit of carbon in the burner. It also prolongs the life of the muffle or crucible for the reason that the air blast is perfectly dry and 80 hot and will not have the disintegrating effect that a moist, cold, air blast, would have, and therefore a correspondingly greater number of heats can be obtained from each container.

The air is forced into the air chamber under pressure from any source such as a blower or fan, and circulates circumferentially around the furnace and since it is compressed in the air chamber there is no danger 90 of its being released before it becomes uniformly heated throughout. It will be noticed also that the outlet pipes J, J, are of less diameter than the inlet pipe B'.

A door at Z is employed for igniting the 95 fuel and for expansion of the products of combustion at the time of lighting.

Having described the invention what I claim as new and desire to secure by Letters Patent is:—

1. A heat treating furnace comprising, a combustion chamber, a cover having a central opening, an annular air compression chamber enclosing the walls of said combustion chamber, a tangentially placed inlet pipe for air at the base of said air chamber, tangential fuel burner nozzles discharging in said combustion chamber, a mixing chamber for fuel and air communicating with each burner nozzle, air passages leading from said air chamber and communicating with said mixing chambers and a muffle horizontally supported in said combustion chamber said muffle extending through the walls of said combustion chamber and air chamber, and a door in the outer wall of said air chamber giving access to said muffle.

2. In a heat treating furnace a combus-

thereon, a cover for said combustion chamber provided with an opening for the passage of the products of combustion from the said combustion chamber to the pre-heating chamber, a bottom for the main chamber provided with an opening, a muffle supported in each chamber, a fuel burner nozzle entering said combustion chamber, and means for supplying a mixture of fuel 10 oil and superheated air to said burners.

4. In a furnace, a combustion chamber, burner nozzles extending therein, fuel supply pipes and air mixers thereon, an annular air chamber heated by said combustion 15 chamber and enclosing the same for supplying hot air under uniform pressure and temperature to said mixers, said supply pipes extending through said mixers and communicating with said nozzles. said

nozzles extending tangentially into said 20 combustion chamber.

5. In a furnace, a combustion chamber, a pre-heating chamber supplied with heat thereby, burner nozzles entering the combustion chamber tangentially, burner supply 25 pipes and air mixers communicating with said burner nozzles, an exterior annular air chamber enclosing said combustion chamber, an air inlet pipe extending tangentially into said air chamber adjacent to its base, 30 and air outlet pipes communicating with said mixers.

In testimony whereof, I hereunto set my hand this 4th day of January, 1919.

JAMES A. GASKILL.
